(57) **CLAIM**

The ornamental design for a roofing material, as shown and described.

DESCRIPTION

FIG. 1 is a top perspective view of an embodiment of a roofing material;

FIG. 2 is a top view of the embodiment shown in FIG. 1; FIG. 3 is a bottom view of the embodiment shown in FIG. 1;

FIG. 4 is a left side view of the embodiment shown in FIG. 1;

FIG. 5 is a right side view of the embodiment shown in FIG. 1;

FIG. 6 is a rear view of the embodiment shown in FIG. 1; and,

FIG. 7 is a front view of the embodiment shown in FIG. 1. The dashed broken lines are for illustrative purposes only and form no part of the claimed design. The dashed-dot lines illustrate unclaimed boundary lines.
